UNITED STATES PATENT OFFICE

EMIL J. DOEHLER, OF BUFFALO, NEW YORK

AEROPLANE FLIGHT BRAKE

Application filed May 18, 1929. Serial No. 364,043.

This invention relates to aeroplane flight brakes and an object of the invention is to provide for increasing the resistance at the rear end of an aeroplane for the purpose of enabling the pilot to bring the plane out of a tail spin in the minimum of drop, while at the same time to cause the aeroplane to come to rest on the ground in the minimum of space.

10. Another object of the invention is to provide for controlling the operation of the wind brake within convenient grasp of the pilot.

Further objects of the invention are to provide in a manner as hereinafter set forth, a 15 device of the character referred to, which is strong, compact, and durable, thoroughly reliable in its operation, highly efficient for its intended purpose, very simple in its method of assembly, and comparatively inexpensive 20 to manufacture and install upon a standard aeroplane of the heavier than air type.

With the foregoing and other objects in view, the invention consists in the novel construction, combination and arrangement of 25 parts as will be hereinafter more specifically described and illustrated in the accompanying drawings, wherein is disclosed an embodiment of the invention, but it is to be understood that changes, variations and modifications, may be made without departing from the 30 spirit of the claims hereunto appended.

In the drawings, wherein like reference characters designate corresponding parts throughout the several views:

35. Figure 1 is a fragmentary, diagrammatic, top plan of the rear portion of an aeroplane fuselage, illustrating the means of controlling the flight brake in accordance with this invention.

40. Figure 2 is a fragmentary diagrammatic side elevation of the rear portion of an aeroplane fuselage, illustrating the means of controlling the rudder flight brake in accordance with this invention, the view being in side 45 elevation.

Figure 3 is a fragmentary side elevation of the rear portion of an aeroplane fuselage illustrating an adaptation therewith of the flight brake in accordance with this invention.

Figure 4 is a detailed vertical sectional view through one of the elevators in accordance with this invention.

Figure 5 is a top plan view of the rear portion of the fuselage, illustrating an adaptation therewith of the device in accordance 55 with this invention.

Figure 6 is a fragmentary portion of the elevator or rudder illustrating in enlarged detail the cross head in accordance with this 60 invention, and

Figure 7 is a sectional view, taken substantially on the line 7—7 of Figure 6.

An aeroplane moves forward through the air by reason of the dynamic force of the air acting upon the wings to sustain the ship in flight and as long as it moves through the air above a certain speed. This latter speed is called "flying speed". Should the aeroplane be made to climb too steeply it would 70 stall, thereby losing its forward motion or flying speed, unless it could immediately be maneuvered into a dive to retain its flying speed, it would begin to spin toward the ground out of control of the pilot. The ship would not respond to the controls because they are cutting the air sidewise and are not receiving the full force of the moving air as they would in forward flight. This 75 invention has a tendency to stop the spin and to enable the ship to pick up flying speed by 80 gravity.

The device is placed upon the rearmost parts of the aeroplane for creating resistance at the tail of the aeroplane. The momentum of the heavy engine in the nose of the aeroplane would move the ship in a forward direction when landing upon the ground and when the flight brake is applied at this time, the same prevents skidding of the fuselage 85 from side to side while at the same time will bring the ship to rest in the minimum of space. When the brake in accordance with this invention is applied in a tail spin, the resistance would be created at the tail, stopping the spin, the weight of the heavy engine 90 in the nose of the ship would draw the ship toward the earth, nose first, as in a straight dive, whereupon the brake would be released, permitting the ship to pick up flying speed by 95 100

gravity. As soon as the ship has flying speed it would be brought out of the dive, or if the engine has stalled, it could be glided to earth under control.

Referring to the drawings in detail, 10 indicates an aeroplane fuselage, which, is equipped with the conventional propeller at the nose driven by any type of motor and having the conventional side planes for sustaining the weight of the ship in the air. The latter features are not shown in the drawings. The numeral 10 indicates a portion of the fuselage devoted to the cock pit wherein the pilot sits. At the rear end of the fuselage 15 there is formed a vertically extending fin 12. At right angles to the fin 12, a pair of stabilizers 13, 14 are rigidly secured to the sides of the fuselage and project in horizontal planes therefrom. A pair of rockable elevators 15, 16, are secured to the trailing edges of the fixed stabilizers 13, 14, and one of the pivots is indicated at 17, in Figures 3 and 4 of the drawings. The rockable elevators 15, 16, are disposed on the opposite side of the fuselage in a horizontal plane and are spaced from the vertical fin 12, as at 17 and 18 to permit the air to have an effect on the rudder and the rudder brake disposed to the rear thereof. The rudder 19 is rockably mounted on the pivot 20 on the trailing edge of the fin 12 and the rockable axis is in a vertical plane at right angles to the axis of the rockable elevators 15, 16.

The rockable elevators and the rudder are 35 provided with the conventional oppositely projecting horns 21, having control cables 22 extending into the cockpit whereby dirigibility and ascent and descent is imparted to the ship, independent of the braking effect in accordance with this invention.

Each of the oppositely disposed rockable elevators 15, 16 and the rudder 19 are equipped in a like manner with planes and extensions to be presently described, which 45 perform the braking action in accordance with this invention and with the exception of the control means, it is believed that a description of one will familiarize the art with the construction of the others. The construction of one of the elevators has been selected 50 as representative of the invention and is shown in enlarged detail vertical section in Figure 4 of the drawings.

Referring particularly thereto, an open 55 rectangular substantially rigid plane 23 is disposed about the elevator 15 and is rigidly supported thereon to the rear of the leading edge thereof by a plurality of strut rods 24. The width of the plane 23 from its trailing to 60 its leading edge is less than the width of the elevator 15 and the trailing edge of the plane 23 is forwardly of the trailing edge of the elevator.

A pair of extensions or wings 25, 26, are 65 rockably mounted on pivots 27, 28, on the

opposite faces of the elevator 15 and axis is in a horizontal plane the same as the axis of the elevator to which they are secured. The area and contour of the extension or wings is substantially the same as the elevator to 70 which it is attached.

The extensions are located between the sides of the plane 23 and the elevator 15 and are rockable therebetween. Intermediate the ends of the elevator 15 it is formed with 75 spaced aligned slots 29, 30, in which is slidably mounted a cross head 31 which is of hollow rectangular configuration. On the outer sides of the cross heads there are formed oppositely disposed trunnions 32, 33, 80 which are pivotally connected to the inner ends of a pair of links 34, 35. The outer ends of the pair of links are pivotally connected to trunnions 36, 37, formed on the inner faces of the extensions 25, 26, midway between the 85 leading and trailing edges thereof, whereby the sliding movement will pull or extend the extensions as desired. A pair of lugs 38 are secured to the stabilizer in the slot to limit the forward movement of the cross head 31 and hold the extensions 25, 26, in extended position shown in Figure 4 of the drawings. When the cross heads are at the other end of the slot the extensions are pulled in abutting parallelism with the stabilizers as is shown 90 in Figure 5 and illustrated in connection with the rudder 19.

The control cable 39 is in the form of a continuous loop, the ends of which are secured to the opposite edges of one side of the cross head as at 40, 41.

The sides of the loop are on the opposite side of the elevator 15 and are trained over a pulley 42 journaled in a slot 43 in the elevator as will be clearly shown by referring 10 to Figure 4 of the drawings. The forward end of the loop is trained over a pulley 44 in the cockpit which is forward of the rockable foot control pedal 45 that has a spring 46 normally urging the pedal rearwardly. The 11 one side of the loop is secured to the pedal and when the pilot's foot is not resting thereon, the extensions will be folded by the spring urging the pedal rearwardly.

The looped control cables 39 which are 12 adapted to control the extensions on the elevators are operated simultaneously to bring about synchronous movement of the extensions and will clearly be understood by reference to the diagram in Figure 1, whereas the 13 looped cable control for the extensions on the rudder are operated independently. The control for the rudder extension is shown in the right of Figure 1 and alone in Figure 2, while the control for extensions for each pair 14 of elevators is shown to the left in Figure 1. It is believed that the control cables will clearly appear and be traceable in Figures 1 and 2 of the drawings, and a more detailed 15 description thereof dispensed with.

A tail skid 47 is provided on the under side of the rear of the fuselage to maintain the rear end thereof in spaced relation to the ground when landing or when resting thereon.

5 From the foregoing description, it will clearly appear that when the aeroplane is landing, or in a tail spin, the operation of the foot levers 45 to the right and the left of the cock pit will cause the cables to move the cross heads located on each elevator and rudder, whereby the extensions 25 and 26 will be moved outwardly in angular relation to the rudders or elevators to which they 10 are attached and will in this position resist the passage of the air through the plane and laterally thereof. This construction will cause a vacuum at the tail of the machine and will have the effect to retard its forward 15 movement in the case of landing and will have a tendency of bringing the aeroplane 20 out of the tail spin while in the air.

What is claimed is:

1. In combination with an aeroplane, a fuselage, a pair of elevators rockably mounted on the opposite sides at the rear of said fuselage and having their axis in a horizontal plane, a rudder rockably mounted on the rear of the fuselage and having its axis in a 25 vertical plane and between said elevators, an open rigid plane disposed about and secured to each of said pairs of elevators and the rudder, a pair of extensions rockably mounted on the opposite sides of the pair of 30 elevators and the rudder between the plane and sides thereof, the axis of said extensions disposed in a plane parallel to the members to which it is attached, means movably mounted on the respective members for rock- 35 ing said extensions, and control means located in the fuselage and connected with said first means for rocking said extensions on their axis.

2. In combination with an aeroplane, a fuselage, a pair of elevators rockably mounted on the opposite sides at the rear of said fuselage and having their axis in a horizontal plane, a rudder rockably mounted on the rear of the fuselage and having its axis in a 45 vertical plane and between said elevators, an open rigid plane disposed about and secured to each of said pair of elevators and the rudder, a pair of extensions rockably mounted on the opposite sides of the pair of 50 elevators and the rudder between the plane and sides thereof, the axis of said extensions disposed in a plane parallel to the members to which it is attached, means movably 55 mounted on the respective members for rock- 55 ing said extensions, and control means located in the fuselage and connected with said first means for rocking said extensions on their axis, said control means arranged to operate 60 the extensions on the elevators in unison and

independent of the control means operating the wings on the rudder.

3. In combination with an aeroplane, a fuselage, a pair of elevators rockably mounted on the opposite sides at the rear of said fuselage and having their axis in a horizontal plane, a rudder rockably mounted on the rear of the fuselage and having its axis in a vertical plane and between said elevators, an open rigid plane disposed about and secured to each of said pair of elevators and the rudder, a pair of extensions rockably mounted on the opposite sides of the pair of elevators and the rudder between the plane and sides thereof, the axis of said extensions disposed in a plane parallel to the members to which it is attached, means movably mounted on the respective members for rocking said extensions, and means for rocking said wings on their axis, said control means arranged to operate the extensions on the elevators in unison and independent of the control means operating the wings on the rudder, said planes being substantially rectangular and disposed to the rear of the leading edges 70 of the members to which they are secured 75 and terminating forwardly of the trailing edges thereof. 80

4. In combination with an aeroplane, a fuselage, a pair of elevators rockably mounted on the opposite sides of the rear of said fuselage and having their axis in a horizontal plane, a rudder rockably mounted on the rear of the fuselage and having its axis in a vertical plane and between said elevators, an open rigid plane disposed about and secured to each of said pair of elevators and the rudder, a pair of extensions rockably mounted on the opposite sides of the pair of elevators and the rudder between the plane and sides thereof, the axis of said extensions disposed in a plane parallel to the members to which it is attached, means movably mounted on the respective members for rocking said extensions, and means for rocking said wings on their axis, said control means arranged to operate the extensions on the elevators in unison and independent of the control means operating the wings on the rudder, said plane being substantially rectangular and disposed to the rear of the leading edges of the members to which they are secured and terminating forwardly of the trailing edges thereof, said first mentioned means including a cross head slidably mounted on the respective members and links pivotally connected to the opposite sides of the cross head and the inner faces of the extensions. 100

5. In combination with an aeroplane, a fuselage, a pair of elevators rockably mounted on the opposite sides of the rear of said fuselage and having their axis in a horizontal plane, a rudder rockably mounted on the rear of the fuselage and having its axis in a vertical plane and between said elevators, an open 105

rigid plane disposed about and secured to each of said pair of elevators and the rudder, a pair of extensions rockably mounted on the opposite sides of the pair of elevators and the rudder between the plane and sides thereof, the axis of said extensions disposed in a plane parallel to the members to which it is attached, means movably mounted on the respective members for rocking said extensions, and means for rocking said wings on their axis, said control means arranged to operate the extensions on the elevators in unison and independent of the control means operating the wings on the rudder, said plane being substantially rectangular and disposed to the rear of the leading edges of the members to which they are secured and terminating forwardly of the trailing edges thereof, said first mentioned means including a cross head slidably mounted on the respective members and links pivotally connected to the opposite sides of the cross head and the inner faces of the extensions, said extensions being of substantially the same area as the respective members to which they are attached.

6. In a control means for aeroplanes, an extended body, means adapted for rockably mounting the body, a pair of wings hingedly mounted on the body on the opposite sides thereof with the axes parallel to the axis of the said body, and means for rocking said wings, and said wings hingedly mounted adjacent the leading edge of said body, a frame disposed about said body for limiting the outward swinging movement of the wings.

7. In a control means for aeroplanes, an extended body, means adapted for rockably mounting the body on an aeroplane, a pair of wings hingedly mounted on the opposite sides of the body with their axes parallel to the axis of the body, a frame disposed about said body for limiting the outward swinging movement of the wings, and means for rocking said wings.

8. In a control means for aeroplanes, an extended body, means adapted for rockably mounting the body on an aeroplane, a pair of wings hingedly mounted on the opposite sides of said body, a frame disposed about said body for limiting the outward swinging movement of the wings, and means for rocking said wings.

9. In a control means for aeroplanes, an extended body, means adapted for rockably mounting the body on an aeroplane, a frame disposed about said body, a pair of wings hingedly mounted on the opposite sides of the body having a portion thereof within said frame, and means for rocking said wings.

In testimony whereof I affix my signature.

EMIL J. DOEHLER.
